UNITED STATES PATENT OFFICE.

STANLEY W. HAYES, OF RICHMOND, INDIANA, ASSIGNOR TO HAYES TRACK APPLIANCE COMPANY, OF RICHMOND, INDIANA, A CORPORATION OF INDIANA.

DERAIL.

Application filed July 21, 1922. Serial No. 576,424.

To all whom it may concern:

Be it known that I, STANLEY W. HAYES, United States citizen, residing in Richmond, county of Wayne, Indiana, have invented 5 the following described Improvements in Derails.

This invention relates to a mounting for a derail, designed particularly but not exclusively for a derail of the type in which the 10 derailing member slides to and from the rail, with an up-and-over movement, in which the derail is adjustable vertically and transversely in accommodation to the rail and in which both adjustments may be made 15 without disturbing the assembled relation between the derailing member and its bearings.

In the three sheets of drawings, Fig. 1 is a 20 plan of the assembled derail in open position; Figure 2 a rear elevation corresponding to Fig. 1; Figure 3 a partial plan showing the bearing member adjusted to a different position; Figure 4 a bottom plan of the bearing member, the adjusting keys being 25 shown in dotted lines and in different positions; Figure 5 is a side elevation of the open derail; Figure 6 is a side elevation of the open derail adjusted in height to suit a lighter rail to which it is shown applied, and 30 Figure 7 is a detail.

Hinged derails have heretofore been made adjustable in height by altering the position of the pivotal axis as by providing pivot pin holes at different heights and at different 35 distances from the rail. These constructions usually require considerable disassembly and rearrangement of the derail parts and are not applicable to derails of the sliding type with which this invention is specially concerned. The construction described and 40 claimed herein segregates as an assembled unit the derailing member and the part of its fixed supporting means which carries the bearings therefor, these bearings being always maintained in their normal relation, and mounts this assembled unit adjustably, both vertically and toward and from the rail, on another part of the fixed supporting means, which latter part is permanently secured to the road bed. By this means the 45 practical work of installing the derail is facilitated, as will later appear. The derail illustrated is of the hook bearing derail type having certain of the features characteristic

of the derail of my Patent No. 1,306,961 55 granted June 17, 1919, but this invention is without limitation to that or any type of derail, nor is it limited to the particular adjusting means, nor to the particular method of dividing the fixed support into adjustable 60 parts or sections.

The sub-base consists of two plates 1, which might however be formed in one piece or connected together if desired.

These plates are provided with spike holes 65 and may rest directly on the ties or road bed. Each plate has at its front outer corner an abutment surface 2 of considerable vertical extent above and below its main horizontal plane and located in a plane transverse to 70 the longitudinal axial plane of the tie plate for insuring its correct location with reference to the rail, these surfaces being designed for contact against some part of the rail, preferably the edge of the rail flange 75 when the plate or sub-base is being installed. The adjustable unit comprises the derail base proper which comprises side walls 3 located between the sides of the adjacent ties and connected at the forward end by 80 cross wall 4 and at the rear end by the roof member 5 and its rear wall 6. Supporting flanges 7 reinforce each side wall 3. The derailing member is mounted in this adjustable base member for movement toward and 85 from the rail and comprises the derail block 8 and its supporting body 9, and the latter is provided adjacent its forward end with studs or other suitable form of bearing 9' designed to slide and pivot in bearing 9" 90 formed in the forward inner faces of the side walls 3 as familiar in the prior art. Preferably, such bearings impart an up-and-over movement to the derail block. The rear bearing for the derailing member is illustrated as a slideway hook bearing of the sort disclosed in my prior Patent No. 1,306,961 above referred to and is indicated without detailed description by the 95 reference numeral 10, which designates the hanger or slideway member, this being preferably located on the top of the body of the derailing member and being hung from a cooperating bearing lug 11 on the rear wall 6. The derailing member may be operated 100 by its attachment lug or lugs or by hand in any usual way. The specific means of adjustment taken for illustration of the inven-

85

90

95

105

tion will now be described but without limitation to any of the particular details thereof. In its lowest position, the base proper rests on the upper end preferably plane surfaces 12, 13 of the respective tie plates, which constitute the sub-base, its supporting flanges 7 being provided with corresponding surfaces 14, 15 and the parts being secured in position by upright bolts 16 which pass through holes 17 in the tie plates and through elongated slots 18 in the flanges 7, the tie plates being recessed or countersunk on the underside to receive the bolt heads so as to secure the bolts against turning. Washers 19 interposed in varying numbers on the bolts between the tie plates and the flanges of the base proper serve to give the latter the required height. The base proper is firmly secured upon these washers and thus 20 upon the sub-base by the nuts 20 locked by the cotter pins 21, a lock washer 22 being associated with the nut, if desired.

Adjustment of the position of the base proper, transversely or toward and from the rail, is effected by the formation of complementary keyway surfaces in the proximate faces of the base and the sub-base, and by the use of spacing members as wedge keys, or keys of different thicknesses in engagement therewith. In the drawings the wall 23 carried by each sub-base member is parallel with the rail or the front edge of the sub-base; the inclined wall 24 being a part of the supporting flange 7 and when the parts 30 are in position being opposed to the wall 23 to form the keyway. The keys 25 are designed by the extent of their insertion or withdrawal to vary the distance of the bearing member from the rail. They are provided with lugs 26 to facilitate these operations. In order to retain the keys in any adjusted position the wall 23 may be provided with teeth 27 of any degree of fineness and the key with corresponding teeth or serrations 28. This gives what may be termed a step adjustment, the gradations being small enough for practical purposes, although obviously a means of adjustment involving the use of a screw, or shims of selected thickness might for example be employed in order to secure more minute changes. As will be apparent the adjusting means is duplicated at each side of the derail.

In conclusion it is further noted that a 55 derail in which the derailing member and the base proper are constructed as an assembled unit adjustable on a sub-base vertically and toward and from the rail may be applied to the road bed without special preparation thereof, such as adzing the ties, accommodation both to local peculiarities of the road bed and to the characteristics of the rail being effected by the double adjustment of the assembled unit on the sub-base, so that 60 a single design of derail block may serve ac-

ceptably in a wide variety of severally differentiated track and road bed situations. Furthermore, a sub-base constructed in two separate and independent parts has special virtue in that each part is mounted individually independently of variation of distance between the ties, and being so mounted affords, by reason of the association with each part of a plurality of adjusting means, the possibility of compensation for inequalities 75 in the road bed at opposite sides of the sub-base and even between front and rear at the same side, the vertical adjustments and to some extent also the horizontal adjustments being individual. 80

Claims:

1. A derail comprising a sub-base adapted to be secured to the road-bed, and an assembled unit including a base and a derailing member provided with bearings on which 85 said member is mounted to slide toward and from the rail, said unit being adjustably mounted on said sub-base.

2. A derail comprising a sub-base adapted to be secured to the road-bed, and an assembled unit including a base and a derailing member provided with bearings on which 90 said member is mounted to move toward and from the rail, said unit being mounted for adjustment on said sub-base vertically and 95 transversely of the rail.

3. In a derailer, a sub-base having spike-holes adapted to be spiked to adjacent ties, and a derail base mounted on said sub-base and adjustable thereon vertically and 100 transversely of the rail.

4. In a derailer of the sliding type, a sub-base adapted to be secured to the road-bed, a derail base mounted on the sub-base, a derailing member adapted to slide to and from the rail on bearings in said derail base, and means for adjusting the derail base on the 105 sub-base without altering the relation between the sliding derailing member and its bearings. 110

5. In a derailer of the type in which the derailing member slides toward and from the rail, a sub-base adapted to be secured to the road-bed, and a derail base carrying said derailing member mounted on the sub-base 115 and adjustable transversely of the rail without altering the relation between the sliding derailing member and its bearings.

6. In a derail of the type in which the derailing member moves toward and from the rail, a sub-base adapted to be secured to the road-bed, and a derail base carrying the derailing member mounted on the sub-base and adjustable thereon both vertically and transversely of the rail without altering the 120 relation between the base and the derailing member. 125

7. A derail comprising a sub-base adapted to be secured to the road-bed, a derail base providing bearings for a slidable de- 130

50

railing member, and means at each side of the derail base for adjusting the same transversely of the rail without disturbing the relation between the slideable derailing member and its bearings.

8. A derail comprising a sub-base adapted to be secured to the road-bed, a derail base providing bearings for a derailing member, means at each side of the derail base for adjusting the same transversely of the rail, and means also located at each side of the derail base for adjusting it vertically without disturbing the relation between the derailing member and its bearings.

15 9. A derail comprising a base and a sub-base having proximate faces adapted to receive interposed means for adjusting the base with reference to the sub-base, and a derailing member mounted on the sub-base for movement to and from the rail.

10 10. A derail comprising a base and a sub-base having proximate faces adapted to receive interposed means for adjusting the base vertically and transversely of the rail.

25 11. A derail having a sub-base adapted to be secured to the road-bed, and a derail base carrying a derailing member, said sub-base and derail base having opposed upright walls, and means adapted to be inserted 30 between said walls to adjust the derail base transversely of the rail.

12. A derail having a sub-base adapted to be secured to the road-bed, and a derail base carrying a sliding derailing member, said sub-base and derail base having opposed upright walls one of which is inclined to the other providing a keyway, and an adjusting key adapted to be inserted in said keyway to adjust the derail base transversely 40 of the rail.

13. A derail comprising a sub-base secured to the road-bed, an assembled unit comprising a derail base provided with bearings and a derailing member adapted to slide thereon to and from the rail, a series 45 of upstanding bolts mounted in said sub-base and extending through slots in the said unit elongated transversely of the rail, and

means for adjusting said unit transversely of the rail.

14. A derail comprising a sub-base secured to the road-bed, an assembled unit comprising a base member provided with bearings and a derailing member adapted to slide thereon to and from the rail, a series 55 of upstanding bolts mounted in said sub-base and extending through slots in the said unit elongated transversely of the rail, washers variable in number associated with said upstanding bolts to determine the 60 height of the unit, and means for securing the unit to the sub-base.

15. A derail comprising a sub-base constructed as two unconnected plates, a base proper mounted on the sub-base, a movable 65 derailing member carried by the base, and means for adjusting the base with reference to the sub-base.

16. A derail comprising a sub-base constructed as two unconnected plates, a base proper mounted on the sub-base, a movable 70 derailing member carried by the base, and a plurality of means for adjusting the base on the sub-base.

17. A derail comprising a sub-base constructed as two unconnected plates, a base proper mounted on both said plates, a movable 75 derailing member carried by the base, and distinct means for adjusting the base with reference to each plate.

18. A derail comprising a sub-base constructed as two unconnected plates, a base proper mounted on both said plates, a derailing member carried by said base, and a plurality of means associated with each of said 80 plates for effecting adjustment in the same direction.

19. In a derail, a pair of unconnected base plates having at their front ends adjacent their outer sides abutment surfaces extended horizontally and vertically at right angles to the longitudinal axes of the base plates for contact with a part of the rail.

In testimony whereof, I have signed this specification.

STANLEY W. HAYES.
